UNITED STATES PATENT OFFICE

2,022,986

STAND FOR ELECTRIC IRONS

Otto Spahr, Philadelphia, Pa.

Application September 15, 1932, Serial No. 633,266

2 Claims. (Cl. 219—25)

This invention relates to a stand for an electric iron and particularly to a stand in which contact is automatically made to produce a flow of electric current through the iron when supported by the stand, the contact being interrupted when the iron is in use with the resultant avoidance of a permanently connected cord.

It has already been proposed to provide a stand for an electric iron in which the iron occupies a sloping position whereby the usual contact elements or prongs thereon will engage cooperating contacts carried by the stand, the contacts on the stand being permanently connected through the medium of a plug and cord to a supply.

It is a broad object of the present invention to improve the stands heretofore designed having particularly in view the facilitation of manipulation of the iron in both locating it upon the stand and removing its therefrom.

One object of the invention relates to the provision of a stand in which the support may have a quite moderate slope while nevertheless proper electrical contact is maintained to serve for the conduction of the heating current. By reason of this the iron is not only readily removed from the stand but is also readily placed thereon, the stand specifically comprising antifriction rollers for supporting the iron which not only facilitate moving the same but also prevent scratching of its roller surface.

Another object of the invention relates to the provision of an improved type of fixed contact. These contacts are arranged in pairs so as to facilitate rather than impede the removal of the iron from the stand. Furthermore, a wiping contact is provided whereby a low resistance at the points of contact is insured by reason of the automatic cleaning action.

Still another object of the invention is the provision of means whereby a circulation of air is maintained beneath the iron support to prevent excessive heating of the board or table on which the stand rests.

A further object of the invention relates to the provision of an adaptor, which used in connection with an iron in which the contact pins are arranged longitudinally of the iron, will provide radially disposed contacts capable of cooperating with the fixed contacts carried by the stand.

Still another object of the invention is the provision of an arrangement whereby the iron may be held transversely of the stand while being prevented under normal conditions from engaging accidentally the electrical contact supporting

means so that this will not be destroyed by the impact of the iron. Other objects of the invention relating particularly to details of construction will be apparent from the following description read in conjunction with the accompanying drawing in which:

Fig. 1 is a perspective view of the stand;

Fig. 2 is a longitudinal vertical section through the same indicating the relationship of an iron thereto;

Fig. 3 is a plan view of the fixed contact supporting elements;

Fig. 4 is a side elevation of an adaptor for an iron having the prongs disposed longitudinally thereof; and,

Fig. 5 is a bottom plan view of the adaptor of Fig. 4.

There is indicated at 2 an electric iron of conventional type in which, as is most usual, the prongs 8 are disposed transversely. The normal distance between these prongs of standard irons is substantially the same so that by the provision of a single stand numerous makes of irons may be accommodated. A heat insulating handle 4 is supported by the usual bails 6.

The stand comprises a suitable base formed of cast-metal providing a sloping iron supporting surface 10. Journalled in the base so as to project above the surface 12 through openings therein are transverse rollers 12 on which the iron 2 may rest and slide. The rollers are mounted to rotate on pins and desirably the rollers and pins are made of different metals in order to promote easy running and avoid binding when the rollers and pins are treated by the iron. If desired the rollers may be bushed for the reception of the pins. Downwardly extending flanges 14 serve to support the iron supporting elements above a board or table. These flanges are cut out as indicated at 16 along the sides and rear of the support so that a circulation of air is provided which will maintain the stand cool and prevent injury to a support.

At the sides of the stand are upwardly extending flanges 18 provided with shoulders 20. If the iron is supported transversely of the stand as indicated in Fig. 1 upon the flanges 18, its movement towards the rear of the stand will be limited by the stops provided at 20. This is desirable inasmuch as an accidental swing of the iron inwardly upon the stand might cause it to engage the contact elements with their possible destruction by repeated impact. When in its normal longitudinal position on the stand the downward

movement of the iron is limited by stop members 22.

Supported by a suitable upward projection of the base is the assembly of the contact elements.

- 5 This assembly comprises a metallic housing indicated at 24 provided with an opening as indicated at 26 for the reciprocation and guidance of the rearmost ball 6 of the iron handles. Located interiorly of the housing 24 is an insulator member 28 to which are secured contact elements 30 having their ends curved inwardly as indicated at 32. These contact elements are formed by a plurality of superposed metallic leaves whereby a substantial flexibility at 32 is provided
- 10 15 so that a spring engagement with the prongs or contact pins 8 results. The contact elements 32 are respectively connected to lead wires extending through suitable insulation of a conventional cord 31. Preferably the electrical connections are permanent although, if desired, plug and socket arrangements may be provided.

By reason of the divergence of the contact elements at 32 in a direction upwardly of the support the removal of the iron is greatly facilitated.

- 20 25 In fact, these elements are desirably of substantial strength so that if it were not for the slope of the support they would tend to eject the iron. The necessary flexibility is attained by reason of the association of the separate leaves. As the
- 30 prongs on the iron engage these leaves a wiping contact occurs which is self-cleaning.

- 35 The arrangement so far described is designed for use with irons in which the prongs 8 are disposed laterally of each other. In some cases, irons are provided with prongs disposed longitudinally of the iron. In order to enable these irons to be used with the stand already disclosed, contacts thereon are provided by the use of an adaptor 34 in the form of a block of insulating material
- 40 45 provided with holes 36. Extending within these holes are contact springs 38 which are respectively electrically connected to exterior buttons 40. If the adaptor is located on an iron of the type just discussed the prongs of which will enter the holes 36, the two buttons 40 will be disposed laterally in positions corresponding to those occupied by the prongs of a wire having the prongs later-

ally disposed. Accordingly with this adaptor an iron of the second type may be used with the stand since the buttons 40 will engage the contact elements at 32 in the same manner as prongs.

By reason of the use of the rollers 12 which provides an antifriction bearing for the iron, the inclination defined by the rollers need only be slightly greater than the angle of repose of the iron on the rollers while nevertheless a proper electrical contact is insured. The angle of the slope which is necessary is quite small as indicated in the drawing so that the iron may be removed from the stand and placed thereon without any substantial vertical movement. This renders the handling of the iron much easier than in the case of those stands in which the angle of slope is of the order of 45°.

It will be obvious that various changes in the embodiment of the invention may be made without departing from the spirit thereof as defined in the accompanying claims.

What I claim and desire to protect by Letters Patent is:

1. A stand for an electric iron carrying contact members comprising a base, spring contact elements supported by the base and arranged to be engaged by said contact members, and a plurality of rollers carried by the base at different levels and adapted to support an iron for movements in an inclined path to bring its contact members into engagement with said contact elements, said contact elements comprising a plurality of superposed metallic leaves.

2. A stand for an electric iron carrying contact members comprising a base, spring contact elements supported by the base and arranged to be engaged by said contact members, and a plurality of rollers carried by the base at different levels and adapted to support an iron for movements in an inclined path to bring its contact members into engagement with said contact elements, said contact elements comprising a plurality of superposed metallic leaves and diverging in a direction up the inclined path whereby they offer a minimum resistance to disengagement of the members therefrom.

OTTO SPAHR.
